CASE STACKING APPARATUS
Warren Du Broff, 350 Carol Court, Highland Park, Ill.
Filed Aug. 28, 1961, Ser. No. 134,489
8 Claims. (Cl. 214—6)

This invention relates to case stacking apparatus, and, more particularly, to apparatus in which a novel mechanism is employed for vertically aligning cases.

With the increasing use of pallets, lift trucks, etc., it is advantageous to stack packages such as cases, cartons, and the like. Thus, the equipment utilized for relocating merchandise can be used to maximum advantage. The savings that are achieved through efficient use of equipment transporting maximum loads can be lost if the load breaks apart during relocation. In other words, the economies achieved through compaction of merchandise can be squandered if the compacted arrangement becomes disarranged. When cartons are stacked four or six high, a small offset of each case relative to the one below can mean a substantial instability. It is, therefore, of prime importance to have stacked cases substantially vertically aligned.

Although mechanisms have been proposed for this purpose in the past, they have, for the most part, had too complex a character to render them suitable for the rough handling usually encountered in a carton manipulating environment. The cartons move along conveyors in a store or shipping room and the equipment must necessarily be rugged. When a complex machine fails to operate properly, there is down-time, which possibly impedes the entire carton handling operation.

It is, therefore, an object of this invention to provide case handling apparatus in the nature of a case upstacker which is characterized by suitable ruggedness yet capable of achieving substantially vertically-aligned stacks of cases.

Another object is to provide vertical aligning means in a case upstacker where the aligning means initially aligns the cases and thereafter retracts a predetermined amount so as to slidably confine the cases during subsequent movements in stacking.

Still another object is to provide a novel vertical alignment mechanism for a case upstacker which follows a predetermined program of gripping and thereafter slidably confines stacked cases and which is automatically adjustable at the conclusion of a given stacking operation.

Other objects and advantages of the invention, both general and specific, may be seen in the details of construction and operation set down in this specification.

The invention will be explained in conjunction with the accompanying drawing, in which—

FIG. 1 is a transverse vertical sectional view through the preferred form of the improved case stacking apparatus as taken on the line 1—1 of FIG. 2;

FIG. 2 is a fragmentary horizontal sectional view through the improved stacker as taken on the line 2—2 of FIG. 1, on a scale enlarge thereover;

FIG. 3 is a fragmentary perspective view of parts of the apparatus at the input end thereof, with the parts in positions changed from those appearing in FIG. 1; and

FIG. 4 is another fragmentary perspective view of parts of the apparatus on that side thereof opposite the one appearing in FIG. 3 when observed toward the input end of the apparatus.

In the illustration given, and with particular reference to FIG. 1, the numeral 10 designates generally a frame positioned astride a conveyor generally designated 11. The frame 10 is equipped with a vertically reciprocable carriage 12 which is adapted to elevate a case or carton 13 by means of lifting dogs 14. The frame 10 is also

2

equipped with holding dogs 15 pivotally mounted as at 16 for supporting a case 13a in an elevated position as part of the development of a stack.

The general operation contemplated here includes the advancement of a case 13 horizontally above the floor 17 and on the conveyor 11. As the case 13 enters the frame 10, it engages a switch arm 18 which electrically couples the carriage motor 19 to a speed reducer 20. The reducer 20 operates through a bell crank 21 and chain 22 to raise the carriage 12 and thus the carton 13. As the carton 13 moves upwardly, it engages the holding dogs 15, pivoting them outwardly until the case reaches a position generally corresponding to that designated 13a in FIG. 1. Thereupon, the holding dogs 15 snap back to the positions shown (under the influence of springs 15a) to support the case in the position 13a and thus permit the now-empty carriage 12 to move downwardly and into a position for elevating a subsequent case. For this purpose, the lifting dogs 14 are pivotally mounted as at 14a, thereby permitting the dogs to pass by a case in the position designated 13 while the carriage 12 is still in the process of being lowered. The chain 22 provides an advantageous function in that it permits the carriage 12 to descend by gravity so that if a subsequent case were under the carriage, there is no positive force exerted by the motor tending to ram the carriage into the case accidentally admitted to the frame 10.

The foregoing general description is characteristic of an upstacker which is seen in my copending application, Serial No. 741,622, filed June 12, 1958, and reference may be made thereto for additional details of construction and operation not found herein.

The above-mentioned application also discloses a height-sensing device generally designated 23, which is operative, upon the completion of a given stack, to retract the holding dogs 15 to a position wherein they permit the completed stack to return with the carriage for issuance from the frame 10.

The frame 10 is equipped with a pair of guide plates 24 and 25 which are arranged generally parallel to the direction of conveyor travel and which are mounted on the frame 10 for movement relative to each other and in a direction transverse of the direction of conveyor travel. For this purpose, the frame 10 is equipped with sleeve bearings 26. The guide plates 24 and 25 are equipped with transversely-extending rods 27 slidably received within the bearings 26.

Causing the relative movement of the guide sheets 24 and 25 is a double-acting air cylinder 28 which is pivotally mounted on the frame 10. The cylinder 28 is equipped with a piston rod 29 which is pivotally connected to an eccentric rod 30 at the outer end thereof. The eccentric rod, at the end opposite its pivotal connection to the piston rod (that pivotal connection being designated by the numeral 31), is affixed to a vertical shaft 32 which is journaled within the frame 10. Also fixed to the shaft 32 is a lever arm 33, and it will be appreciated that as the piston rod 29 is moved relative to the cylinder 28, the lever arm 33 will be pivoted. Pivotally secured to the lever arm 33 as at 34, is a connecting link 35, the link 35, at the other end, being pivotally connected to a lever arm 36 which is fixed to a shaft 37. The shaft 37 is journaled within side bearings 38 provided as part of the frame 10. Thus, the extension or retraction of the piston rod 29 causes a corresponding rotation of the shaft 37. Pinned to the shaft 37 is a lever arm 39 which is pivotally connected to a bracket 40 rigidly secured to the side plate 25. A similar linkage, including elements 35', 36', 37', 39' and 40', is provided relative to the guide sheet 24, the linkage systems for the two side sheets being oppositely arranged so that the sheets move in opposite directions. In other words, retraction of the piston rod

29 brings the sheets 24 and 25 toward each other, while extension of the piston rod 29 separates the two sheets.

The frame is equipped with a switch 41 engageable by the bell crank 21 for reversing the flow of air into the cylinder 28.

It is believed that the mechanism thus far described can be better understood by a brief resume of the operation thereof, and such an exposition follows.

As a case enters the frame 10, as in the position 13, it engages the switch arm 18. The switch 18, through circuitry not shown, couples the motor 19 to the speed reducer 20, causing rotation of the bell crank 21 and elevation of the carriage 12. The switch arm 18 also energizes the cylinder 28 to retract the piston rod 29 and bring the sheets 24 and 25 together to a position where the case 13 is clamped therebetween. At this position, the cylinder 28 cannot force the side sheets 24 and 25 further inwardly. As the elevator crank arm 21 rotates in starting to raise the carriage 12, it contacts the air button 41, which causes the cylinder 28 to reverse, thereby backing off from the case 13 and permitting the same to be elevated by the carriage 12.

The degree to which the side sheets back off is limited to a predetermined clearance through the interposition of a latching mechanism generally designated 42. The mechanism 42 includes a ratchet wheel or cam 43 fixed to the vertical shaft 32 and equipped with ratchet teeth 44. Pivotally mounted on the frame 10 as by shaft 45 is a pawl 46. The pawl 46 is biased into locking position with the ratchet teeth 44 by means of a spring 47. Thus, the extension of the piston rod 29 is able to space the side sheets 24 and 25 apart only a slight distance greater than the spacing they had when gripping the case 13. This permits the sheets 24 and 25 to move toward each other and clamp the case 13, thereby sensing the width and then backing off to provide a predetermined amount of clearance between the sheets 24 and 25 for cases of that size.

When the complete stack is formed, another air button 48 is contacted by the height sensing mechanism and this actuates the pawl release cylinder 49 to rotate the pawl 46 so as to unlatch the ratchet 43 and thereby open the side sheets 24 and 25 to the original setting.

While in the foregoing specification I have set down a detailed description of an embodiment of the invention for the purpose of illustration thereof, many variations in the details herein given may be made by those skilled in the art without departing from the spirit and scope of the invention.

I claim:

1. In the combination of a case upstacker having a frame carrying a vertically reciprocal carriage and holding dogs selectively positionable under a case being elevated on said carriage to support that case, the improved vertical alignment apparatus comprising a pair of sheets mounted on said frame for coactive movement to define a vertical channel for the receipt of superposed cases, means for bringing said sheets toward each other from a first spacing and thereafter to partially retract said sheets away from said cases whereby said sheets have a spacing less than said first spacing, said means being responsive to the vertical movement of a stack of cases for fully retracting said sheets to said first spacing.

2. In combination, a frame equipped with a carriage mounted therein for vertical reciprocal movement, means on said frame for moving said carriage, lifting dogs on said carriage adapted to support a case in a stacking operation, holding dogs pivotally mounted on said frame for selectively receiving and supporting a case elevated by said carriage, a pair of coacting, spaced-apart, aligning sheets mounted on said frame for horizontal movement relative to each other, means on said frame for moving said sheets from a first spacing into clamping relation with a case on said carriage, and means operatively associated with said moving means for limiting the

reverse moving said sheets to a spacing providing a predetermined clearance between the sheets and said case and less than said first spacing, said limiting means being operative to maintain the clearance-providing spacing until a plurality of cases have been stacked.

5 3. The structure of claim 2 in which said moving means includes a cylinder and linkage assembly, said operatively associated means including means on said frame responsive to the upward movement of said carriage for permitting said sheets to move from said clearance-providing spacing to said first spacing.

10 4. The structure of claim 3 in which said responsive means includes upsettable latch means for restricting said linkage means, and also includes means on said frame responsive to the completion of a stack of cases for upsetting said latch means.

15 5. In combination, a frame equipped with a carriage mounted therein for vertical reciprocal movement, means on said frame for moving said carriage, lifting dogs on said carriage adapted to support a case in a stacking operation, holding dogs pivotally mounted on said frame for selectively receiving and supporting a case elevated by said carriage, a conveyor operatively associated with said frame for sequentially advancing cases into said frame and for sequentially removing case stacks from said frame, a pair of vertically oriented guide sheets mounted in said frame for movement transverse to the direction of conveyor travel, power cylinder means on said frame, linkage means interconnecting said cylinder means and guide sheets to move said guide sheets relative to each other, latch means operatively associated with said linkage means for restricting the movement apart of said guide sheets to provide a predetermined clearance for cases being stacked on said frame, means on said frame responsive to the entry of a case therein for raising said carriage and actuating said cylinder to move said guide sheets toward each other, and means on said frame responsive to the raising of said carriage for biasing said latch means to a position to restrict movement apart of said guide sheets to provide said predetermined clearance.

20 6. The structure of claim 5 in which said frame is equipped with means responsive to the completion of a stack for unbiasing said latch means.

25 7. In combination, a frame equipped with a carriage mounted therein for vertical reciprocal movement, means on said frame for moving said carriage, lifting dogs on said carriage adapted to support a case in a stacking operation, holding dogs pivotally mounted on said frame for selectively receiving and supporting a case elevated by said carriage, a conveyor operatively associated with said frame for sequentially advancing cases into said frame and for sequentially removing case stacks from said frame, a pair of vertically oriented guide sheets mounted in said frame for movement transverse to the direction of conveyor travel, power cylinder means on said frame, linkage means interconnecting said cylinder means and guide sheets to move said guide sheets relative to each other, latch means operatively associated with said linkage means for restricting the movement apart of said guide sheets to provide a predetermined clearance for cases being stacked on said frame, means on said frame responsive to the entry of a case therein for raising said carriage and actuating said cylinder to move said guide sheets toward each other, and means on said frame responsive to the raising of said carriage for biasing said latch means to a position to restrict movement apart of said guide sheets to provide said predetermined clearance.

30 8. The structure of claim 7 in which said frame is equipped with means responsive to the completion of a stack for unbiasing said latch means.

35 9. In combination, a frame equipped with a carriage mounted therein for vertical reciprocal movement, means on said frame for moving said carriage, lifting dogs on said carriage adapted to support a case in a stacking operation, holding dogs pivotally mounted on said frame for selectively receiving and supporting a case elevated by said carriage, a conveyor operatively associated with said frame for sequentially advancing cases into said frame and for sequentially removing case stacks from said frame, a pair of vertically oriented guide sheets mounted in said frame for movement transverse to the direction of conveyor travel, power cylinder means on said frame, linkage means interconnecting said cylinder means and guide sheets to move said guide sheets relative to each other, latch means operatively associated with said linkage means for restricting the movement apart of said guide sheets to provide a predetermined clearance for cases being stacked on said frame, means on said frame responsive to the entry of a case therein for raising said carriage and actuating said cylinder to move said guide sheets toward each other, and means on said frame responsive to the raising of said carriage for biasing said latch means to a position to restrict movement apart of said guide sheets to provide said predetermined clearance.

40 10. In combination, a frame equipped with a carriage mounted therein for vertical reciprocal movement, means on said frame for moving said carriage, lifting dogs on said carriage adapted to support a case in a stacking operation, holding dogs pivotally mounted on said frame for selectively receiving and supporting a case elevated by said carriage, a conveyor operatively associated with said frame for sequentially advancing cases into said frame and for sequentially removing case stacks from said frame, a pair of vertically oriented guide sheets mounted in said frame for movement transverse to the direction of conveyor travel, power cylinder means on said frame, linkage means interconnecting said cylinder means and guide sheets to move said guide sheets relative to each other, latch means operatively associated with said linkage means for restricting the movement apart of said guide sheets to provide a predetermined clearance for cases being stacked on said frame, means on said frame responsive to the entry of a case therein for raising said carriage and actuating said cylinder to move said guide sheets toward each other, and means on said frame responsive to the raising of said carriage for biasing said latch means to a position to restrict movement apart of said guide sheets to provide said predetermined clearance.

45 11. In combination, a frame equipped with a carriage mounted therein for vertical reciprocal movement, means on said frame for moving said carriage, lifting dogs on said carriage adapted to support a case in a stacking operation, holding dogs pivotally mounted on said frame for selectively receiving and supporting a case elevated by said carriage, a conveyor operatively associated with said frame for sequentially advancing cases into said frame and for sequentially removing case stacks from said frame, a pair of vertically oriented guide sheets mounted in said frame for movement transverse to the direction of conveyor travel, power cylinder means on said frame, linkage means interconnecting said cylinder means and guide sheets to move said guide sheets relative to each other, latch means operatively associated with said linkage means for restricting the movement apart of said guide sheets to provide a predetermined clearance for cases being stacked on said frame, means on said frame responsive to the entry of a case therein for raising said carriage and actuating said cylinder to move said guide sheets toward each other, and means on said frame responsive to the raising of said carriage for biasing said latch means to a position to restrict movement apart of said guide sheets to provide said predetermined clearance.

50 12. In combination, a frame equipped with a carriage mounted therein for vertical reciprocal movement, means on said frame for moving said carriage, lifting dogs on said carriage adapted to support a case in a stacking operation, holding dogs pivotally mounted on said frame for selectively receiving and supporting a case elevated by said carriage, a conveyor operatively associated with said frame for sequentially advancing cases into said frame and for sequentially removing case stacks from said frame, a pair of vertically oriented guide sheets mounted in said frame for movement transverse to the direction of conveyor travel, power cylinder means on said frame, linkage means interconnecting said cylinder means and guide sheets to move said guide sheets relative to each other, latch means operatively associated with said linkage means for restricting the movement apart of said guide sheets to provide a predetermined clearance for cases being stacked on said frame, means on said frame responsive to the entry of a case therein for raising said carriage and actuating said cylinder to move said guide sheets toward each other, and means on said frame responsive to the raising of said carriage for biasing said latch means to a position to restrict movement apart of said guide sheets to provide said predetermined clearance.

55 13. In combination, a frame equipped with a carriage mounted therein for vertical reciprocal movement, means on said frame for moving said carriage, lifting dogs on said carriage adapted to support a case in a stacking operation, holding dogs pivotally mounted on said frame for selectively receiving and supporting a case elevated by said carriage, a conveyor operatively associated with said frame for sequentially advancing cases into said frame and for sequentially removing case stacks from said frame, a pair of vertically oriented guide sheets mounted in said frame for movement transverse to the direction of conveyor travel, power cylinder means on said frame, linkage means interconnecting said cylinder means and guide sheets to move said guide sheets relative to each other, latch means operatively associated with said linkage means for restricting the movement apart of said guide sheets to provide a predetermined clearance for cases being stacked on said frame, means on said frame responsive to the entry of a case therein for raising said carriage and actuating said cylinder to move said guide sheets toward each other, and means on said frame responsive to the raising of said carriage for biasing said latch means to a position to restrict movement apart of said guide sheets to provide said predetermined clearance.

60 14. In combination, a frame equipped with a carriage mounted therein for vertical reciprocal movement, means on said frame for moving said carriage, lifting dogs on said carriage adapted to support a case in a stacking operation, holding dogs pivotally mounted on said frame for selectively receiving and supporting a case elevated by said carriage, a conveyor operatively associated with said frame for sequentially advancing cases into said frame and for sequentially removing case stacks from said frame, a pair of vertically oriented guide sheets mounted in said frame for movement transverse to the direction of conveyor travel, power cylinder means on said frame, linkage means interconnecting said cylinder means and guide sheets to move said guide sheets relative to each other, latch means operatively associated with said linkage means for restricting the movement apart of said guide sheets to provide a predetermined clearance for cases being stacked on said frame, means on said frame responsive to the entry of a case therein for raising said carriage and actuating said cylinder to move said guide sheets toward each other, and means on said frame responsive to the raising of said carriage for biasing said latch means to a position to restrict movement apart of said guide sheets to provide said predetermined clearance.

65 15. In combination, a frame equipped with a carriage mounted therein for vertical reciprocal movement, means on said frame for moving said carriage, lifting dogs on said carriage adapted to support a case in a stacking operation, holding dogs pivotally mounted on said frame for selectively receiving and supporting a case elevated by said carriage, a conveyor operatively associated with said frame for sequentially advancing cases into said frame and for sequentially removing case stacks from said frame, a pair of vertically oriented guide sheets mounted in said frame for movement transverse to the direction of conveyor travel, power cylinder means on said frame, linkage means interconnecting said cylinder means and guide sheets to move said guide sheets relative to each other, latch means operatively associated with said linkage means for restricting the movement apart of said guide sheets to provide a predetermined clearance for cases being stacked on said frame, means on said frame responsive to the entry of a case therein for raising said carriage and actuating said cylinder to move said guide sheets toward each other, and means on said frame responsive to the raising of said carriage for biasing said latch means to a position to restrict movement apart of said guide sheets to provide said predetermined clearance.

70 16. In combination, a frame equipped with a carriage mounted therein for vertical reciprocal movement, means on said frame for moving said carriage, lifting dogs on said carriage adapted to support a case in a stacking operation, holding dogs pivotally mounted on said frame for selectively receiving and supporting a case elevated by said carriage, a conveyor operatively associated with said frame for sequentially advancing cases into said frame and for sequentially removing case stacks from said frame, a pair of vertically oriented guide sheets mounted in said frame for movement transverse to the direction of conveyor travel, power cylinder means on said frame, linkage means interconnecting said cylinder means and guide sheets to move said guide sheets relative to each other, latch means operatively associated with said linkage means for restricting the movement apart of said guide sheets to provide a predetermined clearance for cases being stacked on said frame, means on said frame responsive to the entry of a case therein for raising said carriage and actuating said cylinder to move said guide sheets toward each other, and means on said frame responsive to the raising of said carriage for biasing said latch means to a position to restrict movement apart of said guide sheets to provide said predetermined clearance.

75 17. In combination, a frame equipped with a carriage mounted therein for vertical reciprocal movement, means on said frame for moving said carriage, lifting dogs on said carriage adapted to support a case in a stacking operation, holding dogs pivotally mounted on said frame for selectively receiving and supporting a case elevated by said carriage, a conveyor operatively associated with said frame for sequentially advancing cases into said frame and for sequentially removing case stacks from said frame, a pair of vertically oriented guide sheets mounted in said frame for movement transverse to the direction of conveyor travel, power cylinder means on said frame, linkage means interconnecting said cylinder means and guide sheets to move said guide sheets relative to each other, latch means operatively associated with said linkage means for restricting the movement apart of said guide sheets to provide a predetermined clearance for cases being stacked on said frame, means on said frame responsive to the entry of a case therein for raising said carriage and actuating said cylinder to move said guide sheets toward each other, and means on said frame responsive to the raising of said carriage for biasing said latch means to a position to restrict movement apart of said guide sheets to provide said predetermined clearance.

said carriage adapted to support a case in a stacking operation, holding dogs pivotally mounted on said frame for selectively receiving and supporting a case elevated by said carriage, a pair of coacting, spaced-apart, aligning sheets mounted on said frame for horizontal movement relative to each other, means on said frame coupled to said sheets for horizontally moving said sheets relative to each other to cause said sheets to grip a case positioned on said carriage and thereafter to cause said sheets to retract to release the grip, and means operatively connected to said coupled means for temporarily limiting

the moving apart of said sheets to a position of partial retraction, said operatively connected means including means responsive to the completion of a stack of cases for permitting said sheets to move farther apart.
